[57] ABSTRACT

A universal strip chart transport mechanism to support and laterally transport a strip chart between a supply roll and a reroll, said strip chart being adapted to be driven by a drive roll and having perforations adjacent opposite edges thereof for snugly receiving

drive pins carried at the opposite ends of the drive roll. The supply roll and reroll are each provided with flanges at the opposite ends thereof, the pairs of flanges at adjacent ends of said rolls being biased toward the other ends of their associated rolls, the biasing forces acting on one pair of flanges being greater than the biasing forces acting on the other pair of flanges. Two modes of operation of the transport mechanism are contemplated, one in which the strip chart is referenced to one edge thereof and another in which the strip chart is referenced to the other edge, the perforations adjacent the remote edge of said strip chart, in each case, being laterally elongated. In said one mode of operation of said transport mechanism, a reference position for said chart is established by said one pair of flanges by the use of retaining means to determine the extreme position to which said one pair of flanges is movable by the associated biasing means. In the alternative mode of operation of said transport mechanism, a reference position for said chart is established by said other pair of flanges by employing the said retaining means to said last mentioned pair of flanges in a fixed position. This arrangement tends to minimize the tendency for the drive pins on the drive roll to become disengaged from the perforations in the chart as the result of lateral expansion and contraction of the chart due to variations in moisture content thereof. In each mode of operation the laterally elongated perforations are at the side of the chart that undergoes the greatest movement as the result of changes in moisture content.

CHART TRANSPORT

BACKGROUND OF THE INVENTION

Chart paper that has been employed in strip chart recorders have heretofore used a series of aligned, uniformly spaced apart round holes adjacent its right or left edge to enable it to be engaged and driven by a drive chart roll sprocket and a series of aligned uniformly spaced apart horizontally elongated slots adjacent its opposite left or right edge to enable it to be engaged and driven by sprockets formed on an opposite end portion of this drive chart roll.

The supply roll commonly referred to as a feed roll and a take up roll, commonly referred to as a reroll spool that are employed with strip chart recorders are provided with movable spring biased end flanges supported on opposite walls of a chart platen which flanges allow the width of the chart to be either uniformly expanded outwardly and/or uniformly contracted inwardly when associated increases and decreases in the moisture content of the chart paper is altered by e.g. a change in the humidity of the atmosphere surrounding the chart.

PROBLEMS

The aforementioned uniform expansion and/or contraction of the chart forces the wall forming the round sprocket holes in the chart to ride in an upward direction over and out of contact with the sprockets on the drive chart roll with which these round sprocket holes are associated and the chart does not return to its driven position while expansion of the chart paper occurs. This chart motion will be in an outward direction against both of the flanges of the feed roll and reroll spools and outward toward the opposite ends of the platen. When the chart paper contracts this chart motion will be in an inward direction away from the opposite walls of the chart platen.

When the round sprocket holes in the chart paper are moved out of the driving contact with the chart drive pins in the drive chart roll in the aforementioned manner the conventional electric motor driven gear drive that is employed to drive this drive chart roll will not be able to carry out its prescribed function, namely, that of transmitting motion to the drive chart roll in order to pull the chart paper from the chart supply roll so that the chart can be wrapped on the reroll at a prescribed rate.

SUMMARY OF THE INVENTION

A chart transport in which the position of the flange of the feed roll and the flange of the reroll that is adjacent the side of the chart that contains the round holes therein provide a stationary reference surface from which expansion or contraction of the chart paper can take place when a change in the moisture content of the chart occurs.

The chart transport structure thus enables the sprocket pins that engage the round holes in the chart paper on the drive chart roll to remain in good contact therewith when humidity changes cause the chart to expand or contract. The motor driven gear train that is employed to drive this drive chart roll will therefore be able to drive the chart at a predetermined rate of speed while adverse moisture content changes in the expansion of the chart occurs.

A better understanding of the present invention may be had when the following detailed description is read in connection with the accompanying drawings in which:

5 FIG. 1 is a partial sectional view taken through the back of an industrial type chart transport showing a platen having unique supports for mounting the ends of a feed roll and reroll chart roll thereon that prevent the sprocket chart drive pins on an associated drive chart 10 roll from becoming disengaged with the round holes on a chart when a change in the moisture content of the chart occurs and

15 FIG. 2 shows how certain parts of the unique chart roll support construction shown in FIG. 1 can be relocated to accommodate a laboratory type of chart roll that has its round holes on the opposite side of the chart from that shown in FIG. 1.

20 The chart transport 10 is comprised of a U-shaped platen 12 that has a rear plate 14, and two side plates 16, 18.

25 The side plate 18 supports a conventional stub shaft 20 on which a motor drive gear 22 is mounted for rotation. The motor and any desired gear reduction train associated therewith is engaged by a motor driven gear 25 of a recorder, not shown, on which the subject chart transport 10 is mounted.

30 The gear 22 in turn is shown in driving contact with a second gear 24 that is fixably connected to a unitary chart driving shaft 26 that in turn is connected for rotation with a driving chart roll 28.

35 The shaft 26 is supported in a longitudinal fixed position and for rotation in molded bearings 30, 32 formed in the left and right ends of the previously mentioned side plates 16, 18.

40 A knurled knob 34 is formed on a left end portion of the driving chart roll 28 for manual rotation of same. A pulley 36 is fixably mounted to a right end shaft 26 so that it is rotatable therewith.

45 A second pulley 38 is mounted on the end of a pin shaft 40 which shaft in turn is provided with a key 42 mounted in a fixed position on its left end by means of a threaded screw connector 44. The upper end of this connector 44 is bent and is shown fitted into a key slot 46 formed in a tube shaped reroll spool 48. A knurled knob 50 is formed on the outer end of the shaft 40 to provide a means of manually rotating the shaft 40, key 42 and the reroll spool 48 that is fixedly attached thereto.

50 The opposite end of the spool 48 is supported by means of a hub portion 52 of the flange 54. The central portion of this flange 54 has a cylindrical apertured wall portion 56 that is of a size that will permit the flange 56 to slide along the pin shaft 58. A molded bearing 59 is formed in the left side plate 16 of the platen 12 to accommodate the mounting of the pin 58 for longitudinal movement thereon. A coil spring 61 is shown mounted on the rivet head type pin 58 which extends in spring biased engagement between the outer left side portion of the hub 52 and the inner wall of the left side plate 16 of the platen 12.

55 The peripheral portion of pin 58 is also provided with two spaced apart ring shaped slots 60, 62. The external cotted 64 is shown retained in engagement with the ring shaped slot 62.

60 A second flange 66 for the reroll spool 48 is shown in FIG. 1 which is similar to that which is in the opposite end position to that shown for the flange 54. The

65

flange 66 has a hub 68 and an inner cylindrical apertured wall portion 70.

The pin shaft 40 on which the flange 66 is mounted is also provided with a ring shaped slot 72 which has an external cotter 74 retained thereon.

A spider spring 76 containing a multiplicity of spring fingers e.g. 78, 80, 82 is shown mounted on the pin shaft 40. This spring is mounted so that it extends between the inner surface of the side plate 18 forming the platen 12 and the outer side surface of the flange 66.

It should be noted at this point that since the external cotter 74 is located in physical contact with and immediately to the right of the hub 68 of the flange 66 that this flange 66 cannot be moved to the right of the position shown in FIG. 1 when expansion of the roll of chart paper 83 being wrapped on a reroll spool 48 occurs during an increase in humidity and in which a related moisture content of the chart paper is increased.

The fixed flange 66 thus establishes a chart stop plate or reference surface from which only transverse expansion of the industrial type of strip chart 83 in a right to left direction against the flange 54 and against the bias of spring 61 can take place. In this way the round holes, for example, 84, 86, 88, 90 on the chart 83 are prevented from moving upward over and out of driving contact with the associated sprocket drive pins 92, 94, 96, 98. Furthermore, in the aforementioned manner the past practice of the disengagement of apertures in the chart paper with its associated sprocket drive will be eliminated.

The supply roll commonly referred to as the feed roll is comprised of a cylindrical spool 100 mounted on a hub portion 102 of the flange 104 and on a hub portion 106 of the flange 108. The central portion of flange 104 has a cylindrical apertured wall 110 that is mounted for sliding laterally along a pin shaft 112. The pin shaft 112 is shown mounted in a fixed position by means of a screw member 114 in a molded bearing member 116 that is formed in the left side plate 16 of the platen 12. A coil spring 118 extends between the inside surface of the side wall 16 and the hub portion 102 of the flange 104 to maintain the flange 104 in spring biased engagement with the left end of the roll of chart paper 83 that is wrapped on the spool 100. In this way the left end of the roll of the chart paper 83 can be expanded in a direction against a direction in which the spring 118 is applying its force to the end of the feed roll of the paper 83.

The central portion of the flange 108 has a cylindrical apertured wall 120 that is mounted in a fixed position on a pin shaft 122 by means of a pair of external cotters 124, 126 that are in turn retained in a fixed position in their associated grooves 128, 130 formed in pin shaft 122.

The rotatable pin shaft 122 is mounted in molded bearing 132 formed in the right side plate 18 of the platen 12 and is restrained from lateral movement by means of the head of a screw member 131 attached thereto.

A spider spring 134 that is similar to the previously mentioned spring 76, which has a multiplicity of spring fingers 136, 137, 138, is shown mounted on the pin shaft 122. The spring 134 is mounted at a location that extends between the inner surface of the side plate 18 forming the platen 12 and the outer side surface of the flange 108.

It should be noted that since the external cotter 128 is located in physical contact with, and immediately to the right of the hub 106 of the flange 108, this flange 108 cannot be moved to the right of the position shown in FIG. 1 when expansion of the roll of the chart paper 83 being pulled off the feed roll 100 occurs during a humidity change in which the moisture content of the chart paper 83 is increased.

The fixed flange 108 thus establishes, in a manner similar to that already described for the flange 66 of the reroll spool 48, a reference surface from which only transverse expansion of chart 83 in a right to left direction against flange 104 and against the bias of spring 118 can take place.

Furthermore, in this manner the round holes for example 84, 86, 88, 90 on the chart 83 are prevented from moving upward over and out of driving contact with their associated drive pins 92, 94, 96, 98. In this way the past practice of disengagement of round apertures in the chart paper 83 with its associated sprocket drive will be eliminated as successive portions of chart paper 83 are pulled by a drive chart roll 28 off a feed roll 100.

FIG. 1 shows a plate 142 which is attached at one end to a central portion of the platen 12 and its free end in spring biased contact with the chart 83 as it is moved between feed roll 100 and drive chart roll 28 so that a drag force will be applied to the chart paper 83.

A series of arrows are shown in FIG. 1 to indicate the direction in which the chart paper 83 is pulled off of the back side surface of feed roll 100 by the drive chart roll 28, once over the drive chart roll, along the external front vertical surface of the platen 14 toward the lower end of the platen and then wrapped into a roll about the previously mentioned reroll driving spool 48.

FIG. 2 shows a laboratory type of chart paper 144 that is of the same width as chart paper 83 shown in FIG. 1. FIG. 2 differs from FIG. 1 in that its chart paper 144 has its driving cylindrical sprocket drive apertures 146, 148, 150, 152 adjacent to a left side of the chart 144 in lieu of being adjacent to right side of chart 83 as shown in FIG. 1.

FIG. 1 shows sprocket drive pins e.g. pins 154, 156, 158, 160 that are equally spaced about and which protrude from the periphery of drive chart roll 28. These pins 154-160 are centrally located and in driving relationship with elongated slots e.g. 162, 164, 166, 168; that are formed in spaced apart relationship adjacent to and along the entire left side of the chart 83.

The sprocket drive pins 92-98 shown in FIG. 2 are located on the right side of the chart 144 and are shown in driving relationship with elongated slots e.g. 170, 172, 174, 176 that are in spaced apart relationship adjacent to and along the entire right side of the chart 144.

To prevent the area of the chart paper 144 adjacent the sprocket pins 154-160 in FIG. 2 from riding up on, over and out of engagement with these drive sprocket pins e.g. 154-160 when the moisture content of the chart is increased, due to a change in humidity, it should be noted that the external cotter 74 and 126, shown in FIG. 1, have been placed in a different position in FIG. 2. More specifically, the external cotter 74 is removed from its FIG. 1 position in which it acts as a stop against left to right movement of the flange 66 and placed into a new FIG. 2 position so that expansion of chart 144 on spool 48 will be able to force flange 66

to the right of the position shown. This chart expansion can occur in FIG. 2 not only because external cotter 74 no longer is in a position to act as a stop for flange 66 as in FIG. 1 but also because the left and right force produced by the coil spring 61 shown in FIGS. 1 and 2 is contructed so that it exerts a greater force than the force of the spider type spring 76 that is acting on the right side of the flange 66.

It can also be seen by comparing FIG. 1 with FIG. 2 that the external cotter 126 that was used to prevent the left to right motion of flange 108, when expansion of charts 83 in FIG. 1 occurred, is now used to prevent the flange 104 from being moved to the right of the position shown by the force of spring 118. The flange 108 will thus be allowed to move to the right of its position shown in FIG. 2 when expansion of chart 144 occurs upon change in its moisture content.

It can be seen that when the external cotter 126 is placed in the position as shown in FIG. 2 rotation of the screw member 114 will selectively allow movement of the pin shaft 112, the cotter 126 and the flange 104 to a desired fixed position that is either to the right or left of the position shown.

The flange 104 will thus act as a reference line from which expansion of the chart 144 can take place only in a left to right direction and in a manner similar to that previously described under the description of FIG. 1.

Selective relocation of the external coppers 74 and 126 between the FIG. 1, and FIG. 2, positions in the manner just described will provide a single chart transport 10 and a good uniform holding, feeding, guiding, driving and rerolling of not only the peripherated type of chart paper 83 shown in FIG. 1 but also the other different type of peripherated chart paper 144 as shown in FIG. 2 when changes in the moisture content of either of these chart papers occur.

It should be noted that the major problem that the unique chart transport 10 presented herein solved is its ability to prevent disengagement of the sprocket drive pin with the circular drive holes in a strip chart when the moisture of the chart is increased and regardless of whether the type of charts being used has its circular drive holes located adjacent its right edge as shown for the industrial type of chart 83 in FIG. 1 or adjacent its left edge as shown for the laboratory type of chart 144 in FIG. 2.

Since very little shrinkage in each of the aforementioned charts 83 and 144 will occur between the small portion of each of these charts that is between the rounded holes and its adjacent edge in the event that the moisture content of these charts is lowered there will be very little possibility of these rounded holes becoming disengaged from their associated drive sprocket

The embodiments of an invention in which an exclusive property or privilege is claimed are defined as follows:

- 5 1. A universal strip chart transport mechanism useful for supporting and longitudinally transporting strip charts having perforations adjacent opposite edges thereof for snugly receiving drive pins carried at the opposite edges of a drive roll, said strip charts in one form being characterized in that the perforations adjacent one of said edges are laterally elongated and in another form being characterized in that the said perforations adjacent the other edge are laterally elongated, thereby allowing lateral expansion or contraction of said charts 10 with changes in the moisture content thereof while in each case minimizing the tendency for the drive pins of said drive roll to become disengaged from the said perforations of said charts, a supply roll and a reroll between which said chart is adapted to be transported, said supply roll and reroll having a flange at each of their opposite ends, means associated with each said flange for biasing said flanges in an axially inward direction, the force of said biasing means in one axial direction on one of said flanges of each said roll being greater than the force on the other of said flanges in the other axial direction, transferable retainer means associated with said supply roll and reroll to establish a reference position for the flanges on which the greater biasing forces are active by determining the extreme positions to which said flanges are movable axially inward by said biasing means, said retainer means being transferable to establish a reference position for the other flanges on which the weaker biasing forces are active to retain each of said last mentioned flanges in a fixed position, whereby both forms of strip charts may be transported by said transport mechanism.

- 20 2. A strip chart transport apparatus as defined in claim 1 wherein an adjustable support means is employed to selectively adjust the position of that supply roll flange to which the stronger biasing force is applied.

- 25 3. A strip chart transport apparatus as defined in claim 1 wherein the flanges of said supply roll and reroll spools are each provided with hub portions that are rotatably supported on the outer surface of a separate stationary pin shaft support member.

- 30 4. A strip chart transport apparatus as defined in claim 1 wherein the flanges of said supply roll and reroll are each provided with a hub portion that is rotatably supported on an individually associated stationary pin shaft support member and wherein said transferable retainer means is an external cotter.
